UNITED STATES PATENT OFFICE.

ROBERT GORTON, OF BROOKLINE, MASSACHUSETTS.

STUD.

1,277,060.

Specification of Letters Patent. Patented Aug. 27, 1918.

Application filed September 13, 1915. Serial No. 50,542.

To all whom it may concern:

Be it known that I, ROBERT GORTON, a citizen of the United States, residing at Brookline, in the county of Norfolk and

5 State of Massachusetts, have invented certain new and useful Improvements in Studs, of which the following is a specification.

This invention relates particularly to studs for hose supporters of the kind shown in my

10 U. S. Patent No. 1,057,396 of March 25, 1913. In that patent I have shown and described a stud comprising a base plate, a headed post secured to the base plate, and a rubber button applied to the headed post. I have also

15 shown and described in said patent a stud comprising a base plate, two headed posts secured to the base plate and a rubber button applied to the headed posts. Experience in the manufacture of said studs has

20 demonstrated that in applying buttons to the headed posts air is sometimes confined or "pocketed" in the post-receiving recesses of the buttons which interferes with a proper attachment of the buttons to the base plates.

25 One of the objects of my present invention is to remedy this objection. Experience has also demonstrated that when two posts are riveted to the base plate by automatic machinery in the manner described in said

30 patent they are sometimes imperfectly applied, being sometimes inclined or disposed at an angle to each other instead of being parallel and at right angles to the base plate as they should be, so that in applying the

35 button to the headed post the latter will not properly enter the post-receiving recesses of the button making the attaching of the button to the base plate difficult and sometimes imperfect.

40 To remedy these defects I now so form the post or posts that provision is made for the escape of air from the post-receiving recess or recesses of the button while the button is being applied, and I so form the heads 45 of the twin posts that they will more readily enter the recesses of the buttons.

Preferably each post is made tubular with an open side from its outer to its inner end to permit the escape of air and the head of 50 each twin post instead of being circular as heretofore is made to extend part-way around the post, thus facilitating in applying the button to the posts should the latter not be truly mounted on the base plate.

55 I also by preference form the post or posts from material taken from the base plate and

bent into the proper shape as I find that combined base plates and posts can be thus manufactured with greater accuracy and economy.

60 The accompanying drawings show preferred embodiments of my invention and also some practical modifications thereof.

Figure 1 is a perspective view of a hose supporter stud made in accordance with my 65 invention.

Fig. 2 is a perspective view of the base plate and button separated before they are connected.

Fig. 3 is a plan view of the blank from 70 which the combined base plate and posts are made.

Fig. 4 is a transverse section through a base plate and button and shows one of the posts in elevation.

Fig. 5 is a longitudinal section of the same.

Fig. 6 is a perspective view on an enlarged scale of a part of the base plate and one of the posts formed from metal taken 80 from the base plate.

Fig. 7 shows a modification and is a perspective view of a base plate with two posts connected therewith, the posts being in this instance made separate and riveted to the 85 base plate.

The base plate A shown in Fig. 1 is preferably made of nickel-plated metal, but it may be made of any suitable material. The button B is preferably made of rubber, but 90 it may be made of some other similar elastic or yielding material. The posts C are made from metal taken from the base plate. The oblong button shown in Figs. 1 to 5 is similar to that shown in my patent above mentioned.

95 The base plate is cut on the lines indicated in Fig. 3 to provide material from which the posts are formed. The metal parts indicated at a in Fig. 3 are bent upwardly on 100 the dotted lines a' until they assume a relation parallel with each other and at right angles to the base plate and they are each worked into a near-cylindrical form and provided with a flange or head c which extends part-way around the outer end of the post, leaving the inner side of the post which faces the companion post unprovided with a flange. Each post is also provided with an open slot c' on its inner side facing its 110 companion post.

When the button is applied to the posts

any air tending to accumulate in the inner ends of the recesses *b* of the button-will escape by way of the slots *c*' and even should the posts be not exactly parallel to the base plate they will properly enter the recesses *b* without crowding the material interposed between said recesses. Experience has demonstrated that posts thus constructed properly enter the post-receiving recesses and 10 take firm hold on the button.

Fig. 7 shows a construction in which the base plate *A*² is provided with posts *C*² formed separately and riveted to the base plate at *c*². These posts have slots *c*³ for the 15 escape of air in the manner before described and they also have heads *c*⁴ which extend part-way only around the outer ends of the posts and therefore this construction embodies some of the features of my invention. 20

I claim as my invention:

1. A stud comprising a sheet metal base plate having a sheet metal post formed integrally therewith, of tubular form and provided with a flanged head and a rubber button having a post-receiving recess smaller at its entrance end than the flanged head and closed at its inner end into which the post extends. 25

2. A stud comprising a sheet metal base plate having a sheet metal post formed integrally therewith, of tubular form having a slot at its side and provided with a flanged head and a rubber button having a post-re- 30 ceiving recess smaller at its entrance end

than the flanged head and closed at its inner end into which the post extends.

3. A stud comprising a base plate, two sheet metal posts, formed integrally with the base plate and each of which is of tubular 40 form slotted at the side and provided with a flanged head and a rubber button having post-receiving recesses each smaller at its entrance end than the flanged head and each closed at its inner end, and into which recess a post extends. 45

4. A stud comprising a base plate, two sheet metal posts, formed integrally with the base plate and each of tubular form and provided at its outer end with a flange extending part way only around it and a rubber button having post-receiving recesses, each of which is smaller at its entrance end than the flanged head of the post which it receives, which is closed at its inner end and 50 into which the post extends. 55

5. A stud comprising a base plate, two parallel hollow posts connected with the base plate and having flanged outer ends and slotted sides and a rubber button having post-receiving recesses smaller than the flanged heads and closed at their inner ends 60 into which the posts extend.

In testimony whereof, I have hereunto subscribed my name.

ROBERT GORTON.
